UNITED STATES PATENT OFFICE.

LANE JOHNSON, OF INGRAM, PENNSYLVANIA, ASSIGNOR TO UNITED ENGINEERING & FOUNDRY COMPANY, OF PITTSBURGH, PENNSYLVANIA, A CORPORATION OF PENNSYLVANIA.

REEL.

Application filed August 5, 1925. Serial No. 48,256.

The present invention relates broadly to the art of metal working, and more particularly to apparatus generally referred to as "reels" effective for coiling strip material, 5 the expression "strip material" being used in its generic sense as being definitive of different structural shapes having such characteristics that it is desirable to coil the same.

At the present time it is customary in the 10 art to which the present invention relates to provide mechanism for coiling strip material, either for the purpose of facilitating handling and transportation thereof or for the purpose of breaking the scale to insure 15 better pickling, or both. The present invention relates broadly to apparatus of this character, and for purposes of illustration is in one instance shown as applied to a reel of the character disclosed in the patent to 20 Florence C. Biggert, Jr., No. 1,492,954, of May 6, 1924, and in another instance is shown applied to a reel of the character disclosed in my prior Patent No. 1,462,411 of July 17, 1923, although it will be apparent 25 that the utility of the invention is not limited with respect to the particular construction of the reel with which it is used.

In reels of the general character shown in the patents referred to, pressure is continuously maintained on the material being 30 coiled by the action of pressure actuated means in the form of levers or rollers, or a combination of the two, having a resilient connection with a cage common to all of 35 the pressure actuated means. This cage in turn has an operative connection with a fluid pressure cylinder adapted to move the same as may be required at predetermined periods in the operation of the reel, and 40 adapted during the coiling operation to compensate for increased pressure exerted on the pressure actuated means by the increase in the diameter of the coil and thereby maintain a substantially constant effective pressure throughout the coiling operation. 45

In actual practice, and particularly where the reel is being used for the coiling of strips of different widths, it has been found necessary to very carefully and accurately control the fluid pressure in the cylinder con-

stituting the compensating means. This has required almost constant attention on the part of the operator and makes the apparatus objectionable to some extent by reason of the attention thus required. 55

The present invention has for one of its objects an improved form of compensating mechanism adjustable to adapt the apparatus to a wide range of material and effective in such manner as to make accurate control of the fluid pressure unnecessary. 60

In the accompanying drawings there are shown, for purposes of illustration only, certain preferred embodiments of the present invention, it being understood that the drawings do not define the limits of my invention, as changes in the construction and operation disclosed therein may be made without departing either from the spirit of the invention or the scope of my broader 70 claims. 65

In the drawings:

Figure 1 is an end elevation, partly broken away and partly in section, illustrating one form of reel embodying the present invention; 75

Figure 2 is a view similar to Figure 1, illustrating the parts in the position they assume upon completion of the coiling operation; 80

Figure 3 is a detail view, on an enlarged scale, illustrating the lost motion and resilient connecting means between the compensating cylinder and the cage; and

Figure 4 is a view similar to Figure 1, 85 illustrating the invention applied to a reel of the character shown in my prior patent referred to.

The general construction of the reel shown in Figures 1-3 is similar to that disclosed in the patent to Biggert No. 1,492,954, and reference may be had to this patent for a complete understanding with respect to details and driving mechanism constituting no part of the present invention. 90

A reel embodying the invention may comprise a base 2 carrying spaced side plates 3 and 4 between which the material being handled is adapted to be coiled. These plates may be held in predetermined spaced rela- 100

tion by the use of spacer sleeves 5 through which may extend bolts 6 as understood in the art.

Rotatably carried by the plates 3 and 4 in any desired manner is a cage 7 having a plurality of inwardly projecting lugs 8 through which extend bolts 9 which at their opposite ends cooperate with bearing blocks 10. These bearing blocks are in turn provided with end studs 11 journaled in the arms 12 of pressure actuated coiling means, each having a pivotal mounting 13 extending between the side plates of the reel. These pivotal mountings conveniently extend through hubs 14 which carry the arms 12 which are preferably spaced to receive the bearing blocks 10 therebetween. The hubs also preferably have secured thereto spaced projecting arms 15, as clearly illustrated in the patent referred to, which carry therebetween pressure rollers 16, the ends 17 of these arms being shaped to constitute guides extending between adjacent rollers.

The side plate 4 is constructed to permit the passage therethrough of a shaft 18 which may be shaped to cooperate with a plurality of sections 19 constituting a collapsible mandrel upon which the material is to be wound. The opposite plate 3 is formed with an enlarged central opening 20 adapted to permit the discharge from the reel of a body of coiled material.

The material M to be coiled and usually in the form of a strip, may be fed to the reel by a pair of gripping and feeding rolls 21. This material passes between the side plates through a suitable opening in the cage 7 and thence through a guide 22. This guide preferably comprises an extension on the arms 15 of the pressure actuated means adjacent the point of entry of the material, whereby the position of the guide will be determined by the diameter of the coil, thereby effectively cooperating with the material as it is fed to the reel throughout the complete coiling operation.

In operation the shaft 18 may be driven in any desired manner, but preferably at a speed greater than the speed of the rolls 21, whereby the material is maintained under some tension during the coiling operation to cause the superimposed layers to tightly engage one another. As the material builds up on the collapsible mandrel or core, it is engaged by the rollers 16 and the guiding portion 17 of the pressure actuated means. This causes the pressure actuated means to move outwardly as the diameter of the coil increases, this outward movement being resisted by compression springs 23 surrounding the bolts 9 and bearing at one end against the bearing blocks 10 and at the opposite end against the cooperating lugs 8. It will thus be apparent that the springs 23 are effective for resisting outward movement of

the pressure actuated means, but that they permit such pressure actuated means to move outwardly relatively to each other and relatively to the cage 7, should such movement be necessary. The guide 22 similarly moves outwardly, thereby being automatically maintained in position to most effectively guide the material.

If the cage 7 is held against any movement during the coiling operation, the increasing pressure exerted by the springs 23 continuously changes the operating characteristics of the pressure actuated means. In order to overcome such a condition of operation it has heretofore been proposed, as illustrated in the patent referred to, to provide a fluid pressure compensating cylinder 24 operatively connected to the cage and adapted to permit rotation thereof against the pressure in the cylinder. Referring to Figures 1 and 2 of the drawings, it will be apparent that as the coil increases in diameter the cage would have a tendency to rotate in a clockwise direction and thereby compensate for the compression of the springs 23. In actual operation, however, it has been found that it is necessary to accurately control the fluid pressure in the cylinder and make changes in this fluid pressure in accordance with the cross sectional area of the material being coiled. This has required extremely close regulation of the fluid pressure on the part of the operator and has necessitated almost constant attention during the coiling operation.

In accordance with the present embodiment of the invention, this objectionable feature of "nursing" the cylinder is obviated by providing a resiliently controlled lost motion connection between the cylinder and the cage. This may be accomplished by extending the arms 12 of one of the pressure actuated means to a point outside of the cage 7 and providing a pin 25 extending between the arms and journaled therein. This pin extends through a slot 26 in the outer end of a piston rod 27 projecting from the fluid pressure cylinder 24. The piston rod at a point intermediate its ends may be provided with a crosshead 28 guided in suitable sideways 29 on the base 2 of the reel for relieving the piston rod from torsional strains. It will be apparent that the slot 26 constitutes a lost motion connection between the pressure actuated means and the fluid pressure cylinder. Due to this lost motion connection the pressure actuated means may move outwardly as before described without the necessity of actually producing any movement of the piston in the cylinder 24. The length of the slot 26 is preferably such as to permit substantially full outward movement of the pressure actuated means before the lost motion is completely taken up. Thereafter, if outward movement of the pressure actuated means continues, the cylinder will come

into operation and compensate for the added compression on the springs 23 due to the increased diameter of the coil effected by the last few turns of material.

5 This outward movement of the pressure actuated means together with rotation of the cage 7 is resisted, however, by a resilient connection herein illustrated as comprising a plate 30 rigidly secured to the outer end 10 of the piston rod 27 by suitable means, such as bolts 31. With this construction the plate 30 is held against movement relatively to the piston rod. The pin 25 passes through links 32 secured to a movable crosshead 33. 15 This movable crosshead may have projecting therefrom one or more guiding sleeves 34 extending through suitable openings in the plate 30 to guide the relative movement between the crosshead and the plate. Also carried by the crosshead is a plurality of rods 35 herein illustrated as being five in number and each having a threaded outer end 36 carrying a thumb nut 37 adapted to be threaded to different positions on the rods 20 to vary the compression or initial load on springs 38 carried thereby. In the illustrated embodiment of the invention, springs 38 are shown as being mounted on only two of the rods 35. It has been found that such a construction may be very effectively used with strips up to 8 inches in width. For slightly wider strips, springs may be added to the central rod 35. Under still other conditions of operation, springs will be applied 25 to the four outer rods only, while for strips of maximum width the springs will be applied to all of the rods. Preferably, under all conditions of operation springs will be maintained on the rods as illustrated in Figure 3, irrespective of what other rods may 30 have springs applied thereto, and the initial load on the springs on these two rods will be just sufficient to close the reel by moving the pressure actuated means to the position 35 shown in Figure 1, and to take up the slack on the other springs. Thereafter, as the diameter of the coil increases the pin 25 will tend to move to the left, as viewed in Figure 3, thereby carrying with it the crosshead 33 40 which will gradually increase the load on the springs 38. This building up of the load on the springs 38 will in turn control the movement of the cage 7 in a clockwise direction, as viewed in Figures 1 and 2, and provides a compensating means in lieu of the 45 fluid pressure cylinder effective for maintaining a substantially constant compression on the springs 23 throughout the coiling operation. By initially determining the 50 proper number of springs 38 and the initial load thereon, it is possible to obtain exactly the right operating conditions for strips of different characteristics and thereby enable the use of a wide range of pressures in the 55 fluid pressure cylinder. Upon the conclu- 60

sion of the coiling operation it will be obvious that the fluid pressure cylinder may be energized for bodily moving all of the pressure actuated means out of contact with the coiled material to permit discharge of the 70 same. This concluding movement accomplished by the fluid pressure cylinder is indicated in dotted lines in Figure 2 of the drawings.

It has also been found desirable to provide 75 means for counterweighting the pressure actuated means. This counterweighting may conveniently be accomplished by extending the arms 12 of one of the pressure actuated means and securing a counterweight 80 39 to the extended arms. This counterweight will preferably be substantially of the order of the weight of the pressure actuated means so as to substantially exactly balance the same. In the event the counterweight actually underbalances the pressure actuated means, this underbalancing may be taken care of by slightly increasing the initial load on the springs 38, while if the counterweight 85 slightly overbalances the pressure actuated means the initial load on the springs 38 may be correspondingly lessened.

It will be apparent that the operation herein obtained by directly securing the counterweight to one of the pressure actuated means and directly connecting the fluid pressure cylinder and the resilient compensating means to another of the pressure actuated means is broadly the equivalent of that which would be obtained by directly counterbalancing the cage 7 or making connection to the cage 7 for the fluid pressure cylinder as disclosed in the patent previously referred to.

In Figure 4 of the drawings there is illustrated a form of the invention in which the counterweight and the resilient compensating means are so secured in position that they are effective simultaneously on all of the pressure actuated means, as will be the 10 case in the preceding figure if these parts were directly secured to the cage and the intermediate springs 23 omitted entirely. In this figure of the drawings, parts corresponding to the parts already described are 110 designated by the same reference numerals, having, however, a prime affixed thereto. The operation of the reel disclosed in this embodiment is substantially the same as that referred to, the material being fed forwardly 115 into a guide 22' by means of pinch rolls 21' into the space defined by the rolls 16' and the shaped ends 17' of the levers 15'. In this embodiment of the invention no core is 120 provided in the coiling space, the rolls 16' being positively driven in a suitable manner, as disclosed, for example, in my prior Patent No. 1,462,411, before referred to. The arms 12' of the various pressure actuated means 125 are directly and rigidly interconnected by 130

means of links 40, whereby all of the rolls 16' move outwardly or inwardly in unison. In addition to the movable rolls, there is preferably provided a roll 41 adjacent the guide 22' which is stationary, this roll defining at all times a predetermined point in the periphery of the material being coiled, to thereby obviate the necessity of providing a movable guide.

- 10 It will be apparent that inasmuch as the counterweight 39' is directly secured to one of the arms 12' which is in turn rigidly interconnected with the other arms, all of the pressure actuated means must move in unison. In like manner the compensating means is effective, as hereinbefore pointed out, for simultaneously acting on all of the pressure actuated means.

The advantages of the present invention 20 arise from the provision of a reel in which the compression exerted during the coiling operation may be maintained substantially constant, irrespective of changes in diameter of the coil and in which the compensation 25 is effected by resilient means, accommoding itself to a wide range of material.

Further advantages are obtained by providing a fluid pressure cylinder having a lost motion connection with the pressure actuated means.

I claim:

1. In a coiler, pressure actuated means adapted to engage the material being coiled, and movable toward and away from such material, and means normally out of operative connection with said pressure actuated means but operative at will for effecting movement of said pressure actuated means, away from the material being coiled, substantially as described.

2. In a coiler, pressure actuated means adapted to engage the material being coiled, and movable toward and away from such material, and means normally out of operative connection with said pressure actuated means but operative at will for effecting movement of said pressure actuated means away from the material being coiled, said pressure actuated means being individually movable relative to said second mentioned means, substantially as described.

3. In a coiler, pressure actuated means adapted to engage the material being coiled and yield relatively and independently during the coiling operation to accurately conform thereto, and yielding means for simultaneously moving all of said means out of engagement with said material, said pressure actuated means being movable relatively to said yielding means during the coiling operation.

4. In a coiler, pressure actuated means adapted to engage the material being coiled, means for moving said pressure actuated means out of engagement with said material,

said means respectively being connected to permit a relative predetermined movement therebetween to permit the same to conform to the material being coiled, and resilient means controlling such relative movement, substantially as described.

5. In a coiler, pressure actuated means adapted to engage the material being coiled, yielding means for moving said pressure actuated means out of engagement with said material, said means respectively being connected to permit a relative predetermined movement therebetween, to permit the same to conform to the material being coiled, and resilient means controlling such relative movement, substantially as described.

6. In a coiler, pressure actuated means adapted to engage the material being coiled and yield relatively and independently during the coiling operation, a combined fluid pressure and resilient means effective uniformly on all of said pressure actuated means for simultaneously controlling all of said pressure actuated means, substantially as described.

7. In a coiler, individually operable pressure actuated means adapted to engage the material being coiled, and resilient means effective uniformly on all of said pressure actuated means for simultaneously controlling all of said pressure actuated means, said resilient means permitting yielding of said pressure actuated means as required during the coiling operation, substantially as described.

8. In a coiler, individually operable pressure actuated means adapted to engage the material being coiled, resilient means simultaneously effective on all of said pressure actuated means, said resilient means permitting yielding of said pressure actuated means as required during the coiling operation, and fluid pressure means for simultaneously effecting movement of all of said pressure actuated means, said fluid pressure means and pressure actuated means being operatively interconnected to permit relative predetermined movement therebetween during the coiling operation.

9. In a coiler, a plurality of individually and relatively movable pressure actuated coiling means adapted to engage the material being coiled, and compensating means comprising springs simultaneously operable on all of said pressure actuated means, substantially as described.

10. The combination with a reel for the coiling of strip material, of compensating means controlling the pressure of material being coiled, said means comprising a plurality of spring carrying members, and a spring on at least one of said members, substantially as described.

11. The combination with a reel for the coiling of strip material, of compensating

means controlling the pressure of material being coiled, said means comprising a plurality of similar spring carrying members, and means for individually controlling the initial compression of a spring on any one of said members, substantially as described.

12. In a coiler, pressure actuated means including a plurality of positively driven rolls, and means for simultaneously moving all of said pressure actuated means in a predetermined direction, said last mentioned means being operatively connected to said pressure actuated means to permit coiling to occur without movement of said last mentioned means.

13. In a coiler, pressure actuated means adapted to engage the material being coiled and to yield relatively and independently during the coiling operation, fluid pressure

control means common to all of said pressure actuated means, resilient means common to all of said pressure actuated means, and an operative connection between said fluid pressure and said resilient means, substantially as described.

14. In a coiler, individually operable pressure actuated means adapted to engage the material being coiled, and resilient means common to all of said pressure actuated means and operatively connected thereto, said resilient means permitting yielding of said pressure actuated means as required during the coiling operation, substantially as described.

In testimony whereof I have hereunto set my hand.

LANE JOHNSON.
